UNITED STATES PATENT OFFICE.

GEORGE W. HOWES, OF DOWAGIAC, MICHIGAN, ASSIGNOR TO BECKWITH COMPANY,
OF DOWAGIAC, MICHIGAN.

GAS OVEN.

Application filed June 25, 1923. Serial No. 647,654.

To all whom it may concern:

Be it known that I, GEORGE W. HOWES, a citizen of the United States, residing at Dowagiac, county of Cass, State of Michigan, have invented certain new and useful Improvements in Gas Ovens, of which the following is a specification.

This invention relates to improvements in gas ovens.

10 The main object of the invention is to provide an improved gas oven which is very efficient in its utilization of the heat units and the heat is very uniformly distributed within the oven.

15 Further objects, and objects relating to structural details, will definitely appear from the detailed description to follow.

I accomplish the objects of my invention by the devices and means described in 20 the following specification. The invention is clearly defined and pointed out in the claims.

A structure which is a preferred embodiment of my invention is clearly illustrated 25 in the accompanying drawing, forming a part of this application, in which:

Fig. I is a fragmentary front perspective view of my improved oven, parts being broken away to show structural details.

30 Fig. II is a plan view of the inner top plate with the baffle plates mounted thereon.

In the drawing similar reference characters refer to similar parts throughout the two views.

35 Referring to the drawing, I provide an outer casing having top walls 1, side walls 2, rear wall 3, and bottom wall 4. The door frame 5 is mounted upon the front of these casing walls, the door 6 being hinged thereto. The burner 7 is disposed in the 40 bottom of the casing.

I provide inner side walls 8 and an inner rear wall 9 disposed in spaced relation to the corresponding outer walls of the casing 45 providing air chambers or spaces between the walls. The inner top wall 10 is arranged upon the upper edges of the side and rear inner walls and has upwardly projecting flanges 11 at its edges, the edges of these 50 flanges abutting the under side of the top wall 1. This inner top wall has a series of circulation openings 12 disposed adjacent its front edge. The inner bottom or deflector plate 13 is disposed above the burner 55 7 with its front and rear edges in spaced

relation to the walls of the casing, providing circulation openings 14 and 15. The top wall 1 has a flue opening 16 disposed centrally and at the rear thereof. A pair of inner baffle plates 17 is disposed between 60 the top walls in spaced relation to embrace this flue opening and extended forwardly therefrom.

A pair of outer baffle plates 18 is disposed in spaced relation to the side walls or side 65 flanges 11 and with their rear ends in spaced relation to the rear wall or flanges, thus providing passages for the products of combustion.

A transverse baffle plate 19 extends between the front ends of the baffle plates 18, this transverse plate being spaced from the circulation openings 12, as shown.

With this arrangement of parts, I secure a very uniform distribution and 70 circulation of the heated products of combustion through and over the oven.

I have illustrated and described my improvements in an embodiment which I have found very practical. I have not attempted 80 to illustrate or describe certain modifications or adaptations which I contemplate as I believe the disclosure made will enable those skilled in the art to which my invention relates to embody or adapt the improvements as may be desired.

Having thus described my invention, what I claim as new and desire to secure by Letters Patent, is:

1. In an oven, the combination of an outer 90 casing comprising top, bottom, rear and side walls and provided with a door, the top wall having a flue opening disposed centrally at the rear thereof, an inner top wall disposed in spaced relation to said casing top wall and having a series of transversely disposed openings adjacent its front edge, said inner wall being otherwise imperforate, a pair of inner baffle plates disposed between said top walls in spaced relation to 95 embrace said flue opening and extending forwardly therefrom, a pair of outer baffle plates disposed in spaced relation to the side walls and to said inner baffle plates with their rear ends in spaced relation to the rear wall, a transverse baffle plate disposed in 100 spaced relation to said openings in said inner top wall to extend between the front ends of said outer baffle plates, a burner, and an inner bottom plate disposed above 105 110

said burner with its front and rear edges in spaced relation to the front and rear wall of the casing providing transverse circulation openings at the front and rear of 5 said bottom plate.

2. In an oven, the combination of an outer casing comprising top, bottom, rear and side walls and provided with a door, the top wall having a flue opening disposed centrally at the rear thereof, an inner top wall disposed in spaced relation to said casing top wall and having a series of transversely disposed openings adjacent its front edge, 10 said inner wall being otherwise imperforate,

15 a pair of inner baffle plates disposed between said top walls and in spaced relation to embrace said flue opening and extending forwardly therefrom, a pair of outer baffle plates disposed in spaced relation to the side walls and to said inner baffle plates with their rear ends in spaced relation to the rear wall, and a transverse baffle plate disposed in spaced relation to 20 said openings in said inner top wall to extend between the front ends of said outer baffle plates.

3. In an oven, the combination of a casing comprising a top wall having a flue opening disposed centrally at the rear thereof, an inner top wall disposed in spaced relation to said casing top wall, a pair of inner baffle plates disposed between said top walls in spaced relation to embrace said flue opening and extending forwardly therefrom, 30

35 a pair of outer baffle plates disposed in spaced relation to the side walls and to said inner baffle plates with their inner ends in spaced relation to the rear of the casing, a transverse baffle plate disposed in spaced relation to the front of the casing to extend 40 between the front ends of the said outer baffle plates, said inner top wall having air circulation openings therein at the front of said transverse baffle plate, a burner, and

45 bottom plate disposed above said burner

with its front and rear edges in spaced relation to the front and rear wall of the casing providing transverse circulation openings at the front and rear of said bottom plate. 50

4. In an oven, the combination of a casing comprising a top wall having a flue opening disposed centrally at the rear thereof, an inner top wall disposed in spaced relation to said casing top wall, a pair of inner baffle plates disposed between said top walls in spaced relation to embrace said flue opening and extending forwardly therefrom, a pair of outer baffle plates disposed in spaced relation to the side walls and to 55 said inner baffle plates with their inner ends in spaced relation to the rear of the casing, and a transverse baffle plate disposed in spaced relation to the front of the casing to extend between the front ends of the said outer baffle plates, said inner top wall having air circulation openings therein at the front of said transverse baffle plate. 60

5. In an oven, the combination of a casing comprising top, rear and side walls, the top wall having a flue opening disposed centrally at the rear thereof, inner side and rear walls disposed in spaced relation to the corresponding casing walls with their upper edges in spaced relation to the top 70 wall, an inner top wall disposed on the upper edges of said inner walls, said inner top wall having upturned flanges at its edges engaging said top wall, said inner top wall having circulation openings therein, 75 and baffle plates mounted on said inner top wall disposed in such relation to said openings therein and said flue opening as to cause the products of combustion to take 80 a circuitous passage from said circulation openings to said flue openings. 85

In witness whereof, I have hereunto set my hand and seal.

GEORGE W. HOWES. [L. S.]
